WORK PRESENTING MECHANISM FOR BLIND STITCH SEWING MACHINES

Filed June 23, 1928

UNITED STATES PATENT OFFICE.

CHARLES W. MUELLER, OF ST. LOUIS, MISSOURI, ASSIGNOR TO LEWIS INVISIBLE STITCH MACHINE COMPANY, OF ST. LOUIS, MISSOURI, A CORPORATION OF MAINE.

WORK-PRESENTING MECHANISM FOR BLINDSTITCH SEWING MACHINES.

Application filed June 23, 1928. Serial No. 287,756.

This invention relates to new and useful improvements in blind stitch sewing machines, although the invention is more particularly directed to the work presenting mechanism thereof.

The invention is especially adapted for use in felling operations generally, and the invention has among its several objects to provide an oscillatory ridge forming disc which is bodily raised and lowered during each complete reciprocation whereby a ridge of material will be formed by the disc during its forward travel and whereby the disc will be lowered from its engagement with the ridge during the backward travel of the disc, and to provide yieldable means for cooperation with the disc to maintain the ridge of material taut during the forward travel of the disc whereby the material will be held against the thrust of the needle.

With these and other objects in view which will more fully appear, the nature of the invention will be more clearly understood by following the description, the appended claims, and the several views illustrated in the accompanying drawings.

In the accompanying drawings which illustrate one form of my invention:

Fig. 1 is a top plan view of a presser foot constructed in accordance with my invention and showing the relation between the foot, the material, the ridge forming disc, the yieldable fingers which cooperate with the material and disc, and the needle.

Fig. 2 is a bottom plan view of the foot, Fig. 3 is a longitudinal sectional view taken through the feed opening in the foot and showing particularly the relation of the disc, the presser foot, the yieldable fingers, the top feed and the needle, and

Fig. 4 is a cross sectional view taken on the line 4—4 of Fig. 1.

Like reference numerals designate corresponding parts throughout the several figures of the drawings.

Referring to the accompanying drawings, my invention comprises a work presenting mechanism for blind stitch sewing machines which includes a presser foot A, a work clamp B, a lower feeding mechanism C, a top feeding mechanism D, and a needle E.

The presser foot A is constructed to be fixedly secured at its rear end to the sewing machine head. This foot includes a

main portion 5 having a centrally located and rearwardly extending slot 6 formed therein. Extending upwardly from the foot on opposite sides of the slot 6 is a pair of ears 7, 7 to which arms 8, 8 are adapted to be respectively attached. These arms 8, 8 are adapted to be adjustably attached at their upper ends to the sewing machine head so as to vary the horizontal plane of the foot. Formed on the upper face of the foot and extending upwardly therefrom are aligned needle guides 9, 10 and 11 respectively. These guides extend in a plane at right angles to the longitudinal axis of the slot 6, the guides 9 and 10 being on the left side of the slot and the guide 11 being on the right side of the slot. The guide 9 and the guide 11 are respectively formed with upstanding walls 9^a and 11^a, said walls being disposed in alignment and arranged on the front side of the guides. The end of the guide 11 adjacent the slot 6 is formed with a recess 12 to receive the point of the needle during its penetrating stroke in order to prevent the point of said needle from springing downwardly during the continued penetrating stroke thereof.

Disposed below the presser foot is a work support 13 and mounted on this work support for oscillation about an axis 14 is a combined ridge forming and work feeding disc 15. This disc is supported for bodily vertical movements during each reciprocating stroke thereof. The axis 14 is disposed directly below the path of needle reciprocation and in parallelism therewith whereby the disc 15 will oscillate in the slot 6 of the presser foot.

The disc 15 is provided along its upper edge with a plurality of teeth 16 and along its lower edge with front and rear concentric portions 17 and 18 of different radii, and with an eccentric or stepped portion 19 intermediate the concentric portions. The disc 15 is supported during its oscillations by a roller 20 which directly engages the concentric peripheral portions 17 and 18 and the eccentric or stepped portion 19 of the disc whereby upon each oscillatory stroke the disc will be bodily raised and lowered. In the position of the disc as shown in Fig. 3, said disc is at the upper end of its movement and at the extreme feeding end of its stroke. It will be observed that when the disc is

oscillated rearwardly, said disc will be lowered by reason of the eccentric or stepped portion 19.

The means of mounting the disc 15 and the means for oscillating the same is fully described in my co-pending application Serial No. 226,398, filed October 15, 1927, for improvements in blind stitch sewing machines, and it is therefore thought that a detailed description of this mechanism is unnecessary.

In the operation of my invention as thus far described, the material to be stitched is positioned between the foot A and the clamp B, and the disc is then moved rearwardly and upwardly to the position shown in Fig. 3, thereby forming a ridge of material and feeding the material a stitch length distance. The needle D is then oscillated on its needle 20 penetrating stroke and consequently the material will be penetrated by the needle while the material is in a state of rest. The disc is then oscillated in the opposite direction and during the first portion of this oscillation the needle remains in the material. This backward oscillation of the disc has a tendency to drag the material towards the front of the machine, or in other words, with the disc. At this time, however, the needle 25 is in the material, and consequently the material is held against being dragged by the disc through the medium of the walls 9^a and 11^a of the needle guides which are disposed on opposite sides of the disc. These guides 30 further serve to prevent the needle from being sprung during the first part of the backward movement of the disc. As soon as the disc reaches the eccentric or stepped portion 19, said disc is lowered and the needle is 35 withdrawn from the material.

In order to hold the ridge of material against the thrust of the needle during the penetrating stroke of the latter, I have provided the presser foot with a pair of spring 40 fingers 21, 21 which are located on opposite sides of the disc 15 and are pivoted at their forward ends by screws 22, 22 to the upper face of the main portion 5 of the presser foot at points in advance of said disc, the fingers 45 extending rearwardly to a point beyond the line of needle reciprocation. The fingers 21, 21 are in the nature of levers, the pivots 22, 22 being the fulcrum thereof. The forward ends of the fingers 21 constitute short lever 50 arms 23, 23 and disposed between these lever arms is a coil spring 24 which normally urges the rear arms 25, 25 into frictional and sliding contact with the material on opposite sides of the disc 15. The rear arms 25 of 55 the levers are bent downwardly from the pivots 22 and thence rearwardly to form horizontal portions from which are movable in recesses 26, 26 formed in the under face of the main portion 5 of the presser foot on 60 opposite sides of the slot 6, the under faces 65

thereof being flush with the underface of the foot in order to give an uninterrupted surface to said foot. The spring fingers 21 are each formed with an upwardly extending stop lug 27 and these stop lugs respectively 70 cooperate with the walls of openings 28 and 29 formed in the main portion 5 of the presser foot to limit the inward movement of the rear arms 25, 25, the width of the openings being sufficient to permit lateral movements 75 of the lugs in order to permit the inner fabric engaging walls of the fingers to register with the side walls of the slot 6. This insures sufficient play of the fingers to accommodate materials of greatly varying thicknesses. 80

Normally the rear arms 25, 25 are held in spaced relation by the stop lugs 27 a distance sufficient to permit the disc 15 during its forward and upward movement to project a 85 node or ridge of material into the slot 6, the movement forcing the rear arms 25, 25 outwardly against the tension of the spring 24. This frictional engagement between the arms 25, 25 and the material serves to retain the 90 material while in its ridge formation against the thrust of the needle penetration, and permits the disc to be readily lowered during the latter part of its return stroke.

It is of course to be understood that the 95 details of structure and arrangements of parts may be variously changed and modified without departing from the spirit and scope of my invention.

I claim:

1. In a sewing machine, the combination with a stitch forming mechanism including a reciprocating needle, of a slotted presser foot, a work support, a toothed ridge forming and fabric feeding disc supported for oscillations on said work support and located in the plane of the slot in the foot, the path of needle reciprocations being in a plane crossing the plane of the disc, means for oscillating said disc, a pair of fabric engaging levers fulcrumed on the foot for cooperation with the fabric on opposite sides of the disc, and means for yieldably retaining the fingers in contact with the fabric. 105

2. In a sewing machine, the combination with a stich forming mechanism including a reciprocating needle, of a slotted presser foot, a work support, a toothed ridge forming and fabric feeding disc supported for oscillations on said work support and located in the plane of the slot in the foot, the path of needle reciprocations being in a plane crossing the plane of the disc, means for oscillating said disc, a pair of fabric engaging levers fulcrumed on the foot in front 115 of the needle for cooperation with the fabric on opposite sides of the disc, and means for yieldably retaining the fingers in contact with the fabric. 120

3. In a sewing machine, the combination 130

with a stitch forming mechanism including a reciprocating needle, of a slotted pressure foot, a work support, a toothed ridge forming and fabric feeding disc supported for oscillations on said work support and located in the plane of the slot in the foot, the path of needle reciprocations being in a plane crossing the plane of the disc, means for oscillating said disc, a pair of fabric engaging levers fulcrumed on the foot for cooperation with the fabric on opposite sides of the disc, and a single spring for yieldably retaining the fingers in contact with the fabric.

15 4. In a sewing machine, the combination with a stitch forming mechanism including a reciprocating needle, of a slotted pressure foot, a work support, a toothed ridge forming and fabric feeding disc supported for oscillations on said work support and located in the plane of the slot in the foot, the path of needle reciprocations being in a plane crossing the plane of the disc, means for oscillating said disc, a pair of fabric engaging levers fulcrumed on the foot in front of the needle for cooperation with the fabric on opposite sides of the disc, and a single spring for yieldably retaining the fingers in contact with the fabric.

30 5. In a sewing machine, the combination with a stitch forming mechanism including a reciprocating needle, of a slotted pressure foot, a work support, a toothed ridge forming and fabric feeding disc supported for oscillations on said work support and located in the plane of the slot in the foot, the path of needle reciprocations being in a plane crossing the plane of the disc, means for oscillating said disc, a pair of fabric engaging levers fulcrumed on the foot for cooperation with the fabric on opposite sides of the disc, said foot being formed with openings on opposite sides of the slot, means for yieldably retaining the fingers in contact with the fabric, and stop lugs respectively carried by the fingers for cooperation with the walls of the openings of the foot to limit the inward movements of the fingers.

45 6. In a sewing machine, the combination with a stitch forming mechanism including a reciprocating needle, of a slotted pressure foot, a work support, a toothed ridge forming and fabric feeding disc supported for oscillations on said work support and lo-

cated in the plane of the slot in the foot, 55 the path of needle reciprocations being in a plane crossing the plane of the disc, means for oscillating said disc, a pair of fabric engaging finger levers fulcrumed on the upper face of the foot in front of the needle, the 60 levers extending downwardly and rearwardly into the slot of the foot and terminating in rear of the path of needle reciprocation, and means for yieldably retaining the fingers in contact with the fabric.

7. In a sewing machine, the combination with a stitch forming mechanism including a reciprocating needle, of a slotted pressure foot, a work support, a toothed ridge forming and fabric feeding disc supported for 70 oscillations on said work support and located in the plane of the slot in the foot, the path of needle reciprocations being in a plane crossing the plane of the disc, means for oscillating said disc, a pair of fabric 75 engaging finger levers fulcrumed on the upper face of the foot in front of the needle, the rear arms of the levers extending downwardly and rearwardly into the slot of the foot and terminating in rear of the path of 80 needle reciprocation, and a single spring disposed between the front arms of the finger levers for yieldably retaining the fingers in contact with the fabric.

8. In a sewing machine, the combination 85 with a stitch forming mechanism including a reciprocating needle, of a slotted pressure foot, a work support, a toothed ridge forming and fabric feeding disc supported for 90 oscillations on said work support and located in the plane of the slot in the foot, the path of needle reciprocations being in a plane crossing the plane of the disc, said disc support including a peripheral cam on the lower edge of the disc, a roller journaled 95 on the work support and in direct contact with the disc, means for oscillating said disc whereby the same will be bodily raised and lowered through said cam and roller during the respective forward and backward oscillating movements thereof, and needle guides on the foot on opposite sides of the slot to retain the needle against springing during the backward oscillation of the disc.

In testimony whereof I hereunto affix my 105 signature.

CHARLES W. MUELLER.
